UNITED STATES PATENT OFFICE.

LOUIS A. ROSETT, OF NEW YORK, N. Y.; MORITZ ROSETT EXECUTOR OF
SAID LOUIS A. ROSETT, DECEASED.

ENVELOPE.

SPECIFICATION forming part of Letters Patent No. 537,365, dated April 9, 1895.

Application filed September 30, 1893. Serial No. 486,860. (No model.)

To all whom it may concern:

Be it known that I, LOUIS A. ROSETT, of the city, county, and State of New York, have invented certain new and useful Improvements 5 in Envelopes, of which the following is a full, clear, and exact description.

My invention relates to improvements in envelopes, and especially to that class of envelopes which are used for carrying valuable 10 or registered packages. It has been found almost impossible to make an envelope which could not be opened by steaming or other means and then resealed, and the object of my invention is to obviate this difficulty, 15 which I do by constructing an envelope with all the seams double and by arranging the fastening flap, together with certain fastening tabs, in such a way that they hold the envelope securely closed, and so that if once loosened they cannot be again fastened without 20 revealing the fact that the envelope has been tampered with.

To these ends my invention consists in an envelope, the construction of which will be 25 hereinafter described and claimed.

Reference is to be had to the accompanying drawings, forming a part of this specification, in which similar figures of reference indicate corresponding parts in all the views.

Figure 1 is a plan view of the blank from 30 which my envelope is formed. Fig. 2 is a rear view of the envelope with the fastening flap open; and Fig. 3 is a rear view of the envelope with the fastening flap secured to the 35 body of the envelope to seal the same.

The envelope blank 10 is provided with 40 projecting end flaps 11 which are adapted to be folded inward on the lines 12, see Fig. 1, and thus form the envelope body, the length of the flaps being such that when folded inward 45 they will overlap so as to make a strong seam, as shown at 13 in Fig. 2. The envelope is provided with side or bottom and top flaps 14 and 15, the former being adapted to fold upward and inward over the flaps 11 to which it is securely gummed, and the tip of the flap 14 is cut off, as shown at 16, although this is not essential. The lower flap 14 is cut to have 50 diagonal edges, as shown.

The envelope is folded on the lines 17 and

18, see Fig. 1, and this causes the upper and lower edges of the envelope to be doubled so that when the envelope is sealed such edges cannot be opened, except by cutting the paper. The envelope is not doubled along the 55 line 18, however, until the package has been inserted in it and the envelope is to be sealed. The flap 15 is then doubled over the back of the envelope in the usual way, except that the fold is made along the line 18 so as to make 60 the double seam at the top, and the flap 15 is provided, at its free edges, with diverging tabs 19 which are adapted to overlap the edges of the flap 14 and be pasted to the flap and to the adjacent body portion of the envelope, 65 as shown in Fig. 3.

The point of the flap 15 is adapted to overlap the central portion of the flap 14, and it will be observed by reference to Fig. 3, that when the flap 15 is fastened down there will 70 be three projecting points on the flap, to wit: the central point of the flap and the two tabs 19, extending in different directions to cover the diagonal edges of the lower flap 14, and if the flap is to be tampered with, that is, loosened by steaming or other means, it will be necessary to bring all three of these points 75 back to their original position when the envelope is resealed, and this is practically an impossibility, so that if the envelope is surreptitiously opened, the fact will be made evident by the displacement of one or more of 80 said projecting points.

It will be noticed that the tabs are projected from the diagonal edges of the top and are 85 elongated in a direction corresponding to the diagonal joints between the lower and side flaps so that when folded, the tabs will overlie and extend along said diagonal joints strengthening and bracing the same longitudinally for a considerable distance along 90 their lengths.

When the envelope is sealed it is desirable to place the wax seals on both tabs 19, as this renders the opening of the envelope much 95 more difficult than if a single seal were applied to the tip of the flap 15.

Having thus described my invention, I claim as new and desire to secure by Letters Patent—

An envelope having a diagonal joint between its lower flap and side flaps having its top flap formed with diagonal edges and provided with tabs projecting from the said diagonal edges and elongated in a direction corresponding to the diagonal joints between the lower and side flaps whereby when folded

the said tabs will overlie and extend along said diagonal joints, substantially as and for the purposes set forth.

LOUIS A. ROSETT.
